[57] CLAIM

The ornamental design for a sprinkler nozzle, substantially as shown and described.

DESCRIPTION

FIG. 1 is a prospective view taken from the top and front of a sprinkler nozzle showing my new design; FIG. 2 is a top plan view thereof; FIG. 3 is a front elevational view thereof; FIG. 4 is a left side elevational view thereof; FIG. 5 is a right side elevational view thereof; FIG. 6 is a bottom plan view thereof; FIG. 7 is a rear elevational view thereof; and FIG. 8 is another prospective view taken from the top and front thereof, showing the sprinkler nozzle in an adjusted position.

*Fig. 1**Fig. 2**Fig. 4**Fig. 3**Fig. 5**Fig. 6**Fig. 7**Fig. 8*
